UNITED STATES PATENT OFFICE.

LYNN EDWIN HILL, OF NORTHFIELD, VERMONT, ASSIGNOR TO CROSS BROS. CO., OF NORTHFIELD, VERMONT, A CORPORATION OF VERMONT.

DESIGN FOR A MONUMENT.

Application filed June 22, 1926. Serial No. 18,139. Term of patent 7 years.

To all whom it may concern:

Be it known that I, LYNN E. HILL, a citizen of the United States, and a resident of Northfield, in the county of Washington and State of Vermont, have invented a new, original, and ornamental Design for Monument, of which the following is a specification, reference being had to the accompanying drawing, forming part thereof.

The figure is a perspective view of a monument, showing my new design.

I claim:

The ornamental design for a monument, substantially as shown.

LYNN EDWIN HILL.
